UNITED STATES PATENT OFFICE.

JAMES T. STANDING, OF ST. LOUIS, MISSOURI.

ADVERTISING-PUZZLE.

1,387,951.

Specification of Letters Patent. Patented Aug. 16, 1921.

Application filed July 28, 1919. Serial No. 313,907.

To all whom it may concern:

Be it known that I, JAMES T. STANDING, a citizen of the United States, and resident of St. Louis and State of Missouri, have invented certain new and useful Improvements in Advertising-Puzzles, of which the following is a specification containing full, clear, and exact description, references being had to accompanying drawings, forming a part thereof.

This invention relates to advertising puzzles and has for its primary object a puzzle used in connection with advertising wherein the name of the advertiser or the name of his goods appears partially, the entire name being added to and finished in a certain length of time.

A further object is to construct an advertising puzzle which will take a predetermined length of time to complete, and the attention of the public being drawn to it during its completion or evolution.

In the drawings,

Figure 1 is a view of my puzzle as it appears during the first period.

Fig. 2 a similar view during the second period.

Fig. 3 a similar view during the third period, and

Fig. 4 a view of the completed puzzle.

In carrying out my invention I make use of a blank 5. This may be either a billboard, a space in a newspaper or magazine, or may be a card such as used in railroad card advertising. On this blank is imprinted a rectangle 6, and the space inclosed within the border lines of this rectangle is subdivided into smaller spaces 7 by means of the crossing lines 8.

In each of the corner spaces is placed a letter which is the commencement of the puzzle. It is to be understood that this puzzle must make use of a word commencing and ending with the same letter. It is also preferable to use a word which has an odd number of letters.

The space on the blank 5 around the rectangle 6 is used to call the attention of the reading public to the puzzle and also to describe the goods, leaving out however

the name of the goods and also of the advertiser so as to arouse the public's curiosity.

In illustrating my puzzle I have made use of the word "America", although it is obvious that any other word or name or combination of words and names commencing and ending with the same letter can be used. I may also use two words if desirable.

In using the word "America" during the first period of the advertising the letter "A" will appear in each one of the corners of the rectangle. After the first period has elapsed the letter "R" is inserted as shown in Fig. 2 and the advertising below it may or may or not be changed, according to the advertiser's inclination. The letter "R" thus appearing will again arouse the public's curiosity and draw attention to the advertisement. On the following period the letters "M" and "C" are inserted, as shown in Fig. 3. This will arouse additional curiosity as to what the word really is, and at the commencement of the final period the letters "E" and "I" are added, thus completing the word and making it possible to read the same in six different directions; that is, two directions horizontally, two vertically and two diagonally.

At the time of the completion of the last word, I find it preferable to remove the lines 8 so that the completed word will appear only within the border, as indicated by the numeral 6. This border may be either a plain line or may be of any fanciful design as desired.

Having fully described my invention, what I claim is:

An advertising puzzle comprising a blank, a rectangular figure formed thereon by joining perpendicular and horizontal border lines, a series of rectangular spaces of an odd number formed on four sides of said rectangular figure and along the margin thereof and a series of intermediate rectangular figures formed on said rectangular figure which are also of odd numbers, certain predetermined letters of a word beginning and ending with the same letter and having an odd number of letters adapted to be inserted in said spaces at predetermined

times, so that when all of said letters of said word have been placed in said rectangular spaces the said word will be spelled out and be arranged along the four sides of said 5 rectangular figure and diagonally twice through said figure, one of said diagonal words intersecting the other.

In testimony whereof, I have signed my name to this specification, in the presence of two subscribing witnesses.

JAMES T. STANDING.
